UNITED STATES PATENT OFFICE.

CHARLES ARTHUR SPEAKMAN, OF NEW YORK, N. Y., ASSIGNOR TO THE AMERICAN LITHOGRAPHIC COMPANY, OF SAME PLACE.

DESIGN FOR AN ORNAMENTAL PRINT OR PATTERN FOR CIGAR-BOXES.

SPECIFICATION forming part of Design No. 28,374, dated March 15, 1898.

Application filed January 29, 1898. Serial No. 668,491. Term of patent 7 years.

To all whom it may concern:

Be it known that I, CHARLES ARTHUR SPEAKMAN, a citizen of the United States, residing at New York city, in the county of New

5 York and State of New York, have invented and produced a new and original Design for an Ornamental Print or Pattern for Cigar-Boxes, of which the following is a specification, reference being had to the accompanying drawing, forming a part thereof.

10 My design is intended for the ornamentation of a cigar-box.

In the accompanying drawing the design is shown on the lid or cover of a cigar-box, the 15 view being a front elevation with the lid raised.

The design comprises an oblong horizontal panel having a deep border ornamented by scroll and fret work. On the right side of the 20 panel is shown in perspective a set of china-

ware. In the foreground, also in perspective, is shown a match-safe with the lid open and the matches exposed, a lighted cigar resting upon a plate, and a wine-glass.

In the upper left-hand corner of the panel 25 the design also shows a shield surmounted by a crown and having a castle in its field. On each side of the shield is arranged a branch of green leaves, the stem ends of the branches crossing under the shield. 30

I claim—

The design for an ornamental print or pattern for cigar-boxes substantially as shown and described.

In testimony whereof I affix my signature 35 in the presence of two witnesses.

CHARLES ARTHUR SPEAKMAN.
